US0D1048173S

(12) **United States Design Patent** (10) Patent No.: **US D1,048,173 S**
(45) Date of Patent: ** Oct. 22, 2024

(54) **KEY FOR A PRINT LIQUID SUPPLY CAP**

(71) Applicant: **Hewlett-Packard Development Company, L.P.**, Spring, TX (US)

(72) Inventors: **Bernd Karlsboeck**, Sant Cugat del Valles (ES); **Judson M. Leiser**, Corvallis, OR (US); **Miquel Boleda Busquets**, Sant Cugat del Valles (ES); **Michael E. Peterschmidt**, Corvallis, OR (US)

(73) Assignee: **Hewlett-Packard Development Company, L.P.**, Spring, TX (US)

(**) Term: **15 Years**

(21) Appl. No.: **29/889,839**

(22) Filed: **Apr. 17, 2023**

Related U.S. Application Data

(63) Continuation of application No. 29/776,438, filed on Mar. 30, 2021, now Pat. No. Des. 986,318, which is a continuation of application No. 29/656,528, filed on Jul. 13, 2018, now Pat. No. Des. 921,748.
